STRADDLE BENCH

Jack E. Schafer, 4643 Sunset Drive, Sacramento, Calif.
95822, and Jack C. Ryder, 1050 W. Capitol Ave., West
Sacramento, Calif. 95814

Filed Sept. 16, 1966, Ser. No. 3,886

Term of patent 14 years

(Cl. D15—11)

FIG. 3

FIG. 4

FIG. 5

FIG. 6

FIGURE 1 is a front perspective view of a straddle bench, showing our new design;

FIGURE 2 is a side elevational view, the opposite side being substantially similar in appearance;

FIGURE 3 is a top plan view;

FIGURE 4 is a bottom plan view;

FIGURE 5 is a rear elevational view; and

FIGURE 6 is a front elevational view thereof.

We claim:

The ornamental design for a straddle bench, as shown and described.
